FIG. 1 is a perspective view of a cup insulation sleeve showing my new design, the longer broken lines denote unclaimed stitching, unclaimed inner layer and lower portion of the sleeve; the shorter broken lines denote a boundary of the unclaimed lower portion.

FIG. 2 is a front view thereof.

FIG. 3 is a rear view thereof.

FIG. 4 is a left side view thereof.

FIG. 5 is a right side view thereof.

FIG. 6 is a top plan view thereof.

FIG. 7 is a bottom plan view thereof.

FIG. 8 is a perspective view of an alternate embodiment of FIG. 1, the longer broken lines denote the unclaimed stitching and lower portion of the sleeve; the shorter broken lines denote a boundary of the unclaimed lower portion.

FIG. 9 is a front view of FIG. 8.

FIG. 10 is a rear view of FIG. 8.

FIG. 11 is a left side view of FIG. 8.

FIG. 12 is a right side view of FIG. 8.

FIG. 13 is a top plan view of FIG. 8; and,

FIG. 14 is a bottom plan view of FIG. 8.
